His Attorney

UNITED STATES PATENT OFFICE

CHARLES A. BROOKS, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

REMOTE CONTROL SYSTEM

Application filed August 23, 1928. Serial No. 301,626.

My invention relates to remote control systems of the type involving a control station, a plurality of remote stations, and a normally closed circuit extending from the control station to the remote stations and including in series a code transmitting contact in the control station and code selecting means at each remote station.

One object of my invention is the provision, in a system of the character described, of means at a remote station for placing a low resistance shunt across the control circuit in the event of a break in the circuit, so that such circuit may still be operated between the control station and such remote station.

I will describe one form of control system embodying my invention, and will then point out the novel features thereof in claims.

20 The accompanying drawing is a diagrammatic view showing one form of control system embodying my invention.

Referring to the drawing, the reference character G designates a control station, and 25 the reference characters A⁰ A¹ and A² designate three remote stations. Located in the control station is a code transmitting relay C provided with a normally closed code transmitting contact 3. Each remote station 30 is provided with a code receiving relay R and with selecting means S governed by a normally open back contact 21 of the associated code receiving relay R. Each remote station is also provided with a code transmitting relay C having a normally closed back contact 3. The control station is further provided with a code receiving relay R the back contact 21 of which controls a code receiving selector means S^g. The contact 35 3 of each code transmitting relay C⁰, C¹ and C² is normally excluded from the control circuit, but may be included in the control circuit when a return indication relay T⁰, T¹ or T² is energized.

40 The normally closed control circuit is from battery 2 at the control station G, through contact 3 of code transmitting relay C, wire 4, relay R⁰, battery 2⁰, contact 30-31 of return indication relay T⁰, wires 32 and 33, 45 special relay D at station A⁰, wire 34 relay

R¹, battery 2^A, contact 5-6 of return indication relay T¹, wires 7 and 8, special relay D at station A¹, wire 9, relay R², battery 2^B, contact 10-11 of return indication relay T², wire 12, line wire 13, and relay R at the 55 control station G to battery 2. It will be noted that this circuit includes contact 3 of the code transmitting relay C at control station G, and that it includes each of the code receiving relays R⁰, R¹ and R², but that 60 it does not include the code transmitting contacts 3 of relays C⁰, C¹ and C² at the remote stations A⁰, A¹ and A².

When a signal is to be transmitted from the control station, relay C is intermittently energized by means having nothing to do with my present invention, with the result that contact 3 is intermittently opened. This causes intermittent de-energization of the receiving relays R⁰, R¹ and R², with the 70 result that the selectors S⁰, S¹ and S² are operated in the usual and well known manner to select one of the remote stations and to give a suitable indication at the selected station. 75

When a signal is to be transmitted from remote station A¹ to the control station G, the return indication relay T¹ is first energized, thereby opening the main circuit at contact 5-6 of this relay and closing a shunt across the main circuit, which shunt passes from battery 2^A through contact 5-14 of relay T¹, back contact 3 of code transmitting relay C¹ and wire 16 to line wire 13. Relay C¹ is then intermittently energized to intermittently open its back contact 3, with the result that the receiving relay R at the control station G is intermittently de-energized to operate the selectors S^g. When the return indication is completed, relay T¹ again becomes deenergized, so that the parts are restored to their normal positions wherein they are ready for the transmission of a signal from the control station G. When a return signal is to be transmitted from remote station A², relay T² is first energized, and the signal is then transmitted by contact 3 of relay C². Similarly, when a return indication is to be transmitted from station A⁰, relay T⁰ is first energized, 90

95

100

and the signal is then transmitted by contact 3 of relay C⁰.

A system of the type thus far described is disclosed and claimed in an application for 5 Letters Patent of the United States filed by C. S. Snavely on May 14, 1929, Serial No. 362,948, for remote controlling apparatus.

I will now assume that a break occurs in the control circuit between stations A¹ and 10 A², as for example at point 22 in wire 9.

It will be seen that in the absence of any special provision this would prevent the transmission of a signal from the control station G to either remote station A⁰ or A¹.

15 Located at station A¹, however, is a special relay D which is included in the normal control circuit and which is therefore de-energized each time that the code transmitting contact 3 of relay C is opened. Relay D

20 controls a slow pick-up device E, the circuit being from terminal B of a suitable source of current, through contact 17 of relay D, operating winding of device E, and a back contact 18 of a cut-out relay F to terminal

25 O of the same source of current. The time interval required for contact 19 of the slow pick-up device E to close is substantially greater than the maximum interval during which contact 3 of relay C is open while a

30 code is being transmitted from the control station G. It follows that contact 19 of the device E remains open during the transmission of the code from station G. If the control circuit becomes open; however, at a

35 point such as at 22, relay D will remain de-energized, and contact 19 of the slow pick-up device E will close. The cut-out relay F will then become energized through a pick-up circuit which includes contact 19 of the

40 device E. Cut-out relay F is provided with a stick circuit which passes from terminal B, through back contact 17 of the special relay D, front contact 20 of relay F, and the winding of relay F to terminal O. It

45 follows that when the relay F once becomes energized, it will remain energized as long as relay D remains de-energized. When relay F becomes energized, its back contact 18 opens, thereby de-energizing the slow pick-

50 up device E. The closing of contact 23 of the cut-out relay F closes a shunt across the control circuit at station A¹, which shunt passes from wire 7, through wire 24, front contact 23 of relay F, and wires 25 and 16

55 to line wire 13. The break in the line at 22 will also cause relay D at station A⁰ to remain open long enough to energize relay F at this station, thereby closing a second shunt across the control circuit at station

60 A⁰. This shunt passes from wire 32, through contact 35 of relay F and wires 36 and 37 to line wire 13. Relay D at station A⁰ will then become energized by a circuit which passes from battery 2^A,

65 through contact 5—6, wires 7 and 24, con-

tact 23, wires 25, 16, 13, 37 and 36, contact 35, wires 38 and 33, relay D, wire 34, and relay R¹ to battery 2^A. The shunt at station A⁰ will therefore open due to the opening of the stick circuit for relay F at the front contact of relay D, but the shunt at station A¹ will remain closed. The opening of relay F will also open the circuit just traced for relay D, but the latter relay will be kept energized through the main circuit because it is no longer shunted by contact 35 of relay F. With this latter shunt closed, the operation of the code transmitting contact 3 at station G will cause operation of the code receiving relays R⁰ and R¹ at stations A⁰ and A¹, and so it follows that the operator at station G can transmit signals to stations A⁰ and A¹. When the break in the line is repaired, relay D will at station A¹ become energized, with the result that the stick circuit for relay F will be opened, so that this relay will become de-energized and will remove the shunt across the line at station A¹. The circuit for relay D, by which this relay becomes energized when the break in the line is repaired, is from battery 2^B, through contact 10—11 of relay T², wires 12, 13, 16 and 25, contact 23 of relay F, wires 24 and 8, relay D, wire 9, and relay R², to battery 2^B.

90 While station A¹ is transmitting, relay D will be deprived of current, so that this relay will be open and relay F will be closed. As soon as station A¹ stops transmitting, relay D will close and relay F will open.

95 Ordinarily a remote control station embodying my invention will include more than three remote stations, and when this is so, each station except the one farthest from the control station G may be provided with cut-out apparatus comprising the special relay D, the slow pick-up device E, and the cut-out relay F, so that when a break in the line occurs between any two remote stations, communication can still be maintained between the control station and all of the remote stations up to the point at which the break has occurred.

100 Although I have herein shown and described only one form of remote control system embodying my invention, it is understood that various changes and modifications may be made therein within the scope of the appended claims without departing from the spirit and scope of my invention.

110 Having thus described my invention, what I claim is:

1. In a remote control system, a normally closed circuit extending from a control station to a plurality of remote stations, said circuit including in series a code transmitting device at the control station, code transmitting means at each remote station and a source of energy at each station, a protection relay at each remote station except the last

serially included in said circuit, means at each remote station except the last for placing a shunt across said circuit at such station so that the local source of current and the local code responsive means are included in the portion of the circuit leading to the control station and the local protection relay is included in the portion of the circuit leading to the next more remote station, means whereby each of said protection relays causes the corresponding shunting means to complete the corresponding shunt when said normally closed circuit is broken for a time interval greater than the maximum time interval said circuit is broken during the transmission of codes by the code transmitting means, whereby upon a break in the circuit at any point the protection relay at each remote station becomes de-energized to cause the operation of the associated shunting means and remains de-energized until the circuit therefor is completed by the shunt applied by the relay at the more remote station or by the repair of the break in said circuit.

2. In a remote control system, a normally closed circuit extending from a control station to at least a first and second remote station, said circuit including in series a code transmitting device at the control station, code responsive means at each remote station and a source of energy at each station, a protection relay at the first remote station serially included in said circuit, means at said first remote station for placing a shunt across the circuit at such station so that the local source of current and the local code responsive means are included in the portion of the circuit leading to the control station and the protection relay is included in the portion of the circuit leading to the second remote station, means whereby said protection relay causes the shunting means to complete the shunt when said normally closed circuit is broken for a time interval greater than the maximum time interval said circuit is broken during the transmission of codes by the code transmitting means, whereby upon a break in the circuit between said first and second remote stations, the protection relay becomes de-energized to cause the operation of said shunting means and remains de-energized until the circuit therefor is completed by the repair of the break in said normally closed circuit.

In testimony whereof I affix my signature.
CHARLES A. BROOKS.
